UNITED STATES PATENT OFFICE.

TIMOTHY HOLLAND, OF CINCINNATI, OHIO, ASSIGNOR TO BLANCHE I. HOLLAND, OF NEW YORK, N. Y.

MOLD FOR RADIATOR-SECTIONS.

SPECIFICATION forming part of Letters Patent No. 778,861, dated January 3, 1905.

Application filed September 28, 1904. Serial No. 226,263.

To all whom it may concern:

Be it known that I, TIMOTHY HOLLAND, a citizen of the United States of America, and a resident of Cincinnati, county of Hamilton, State of Ohio, have invented certain new and useful Improvements in Molds for Radiator-Sections, of which the following is a specification.

The object of my invention is a mold in which the core is not liable to be broken by the molten metal and may be readily centered in the mold-section, which is manipulated easily in use and in which there is a simple and efficient means for releasing the gases from the core. This object is attained by the means illustrated in the accompanying drawings, in which—

Figure 1 is a side elevation of a radiator-section to be cast in the mold embodying my invention. Fig. 2 is a central sectional view of the core. Fig. 3 is a central sectional view of the flask, mold-sections, and core after the latter has been centered and before the mold is turned to its vertical position to receive the molten metal. Fig. 4 is a detail end view of the table when the flask is in a vertical position. Fig. 5 is a sectional view of the radiator section, taken upon line $x-x$ of Fig. 1.

Referring to the parts, the nowel A and the cope A' have their edges, top, and bottom planed perfectly level, the nowel to rest squarely upon plate or table A² and the cope A' to fit flatly against the top plate A³. The nowel and the cope have the customary brackets $a^4 a^5$ to receive the dowel-pins $a^6 a^7$ for centering the flasks upon each other.

The plate or table A² has at each of its ends centrally-located trunnions $a^8 a^9$, which are adapted to fit into the journal-bearings in stationary standards B B'. Plate A³ has at its ends perforations $a^{10} a^{11}$, and plate A² has perforations $a^{12} a^{13}$, which stand opposite perforations $a^{10} a^{11}$, respectively. The core-prints $c c'$ of the molds C C' extend to the plates A² A³ and are made larger than the perforations a^6 to a^9 .

The core consists of three parallel branches $d^1 d^2 d^3$, lying in the same plane and having central channels $d^3 d^4 d^5$, the branches being

connected at their ends, as well as the channels, the ends of the branch d^1 having upon each side projections d^6 of a diameter equal to that of the core-prints $c c'$, the ends d^6 being of a length such that when the core is in position for molding the ends d^6 bear flatly against the table A² and the plate A³. These ends d^6 have channels d^7 in communication with channels $d^3 d^4 d^5$ and which register with perforations a^6 to a^9 .

In use the plate A² being brought to its horizontal position the nowel A is laid upon it. Then the core D is placed in position with its ends d^6 fitting the core-prints $c c'$ and bearing flatly against table A². Then the cope A' is placed over the core, the ends d^6 registering with the core-prints $c c'$, and then the top plate A³ is placed on the cope with its perforations $a^6 a^7$ registering with the channels d^7 . Then the parts are clamped together by clamps E. Since the edges of the nowel and cope have been made perfectly true and the table A² and plate A³ are likewise perfectly level, when the parts are clamped together thus it is seen that the ends d^6 bearing against the plates A² A³ cause the core D to be centered accurately in the mold. Before the molten metal is poured into the flask the whole flask is turned, together with the plate A², about the trunnions $a^8 a^9$ to a vertical position, such as shown in Fig. 4, and then the molten metal is poured in through the gate a^{10} . It is seen that the tendency of the molten metal to cause the core to be carried upward, which tendency brings a bending strain upon the central part of the core, is well resisted by the core in this position, because the parts $d^1 d^2 d^3$ stand vertically above each other and have a greater resisting power than they would have were they in a horizontal position such that one would not assist the other in resisting the bending strain. The gases arising in the core are carried away quickly through the perforations b .

What I claim is—

1. In a mold for hollow castings the combination of a nowel and a cope each having straight edges, a flat table upon which the nowel rests, a flat plate to fit upon the cope, mold-sections having core-prints extending to the table and

the plate and a core having ends to pass through the prints and bear against the table and the plate.

2. In a mold for hollow castings the combination of a nowel and a cope each having straightedges, a flat table upon which the nowel rests having perforations therein, a flat plate to fit upon the cope, mold-sections having core-prints extending to the table and the plate and

10 registering with the perforations in the plate, a core having ends to pass through the prints and bear against the table and the plate and having channels therethrough the ends of which register with the perforations in the plate.

3. In a mold for hollow castings the combination of a nowel and a cope each having straightedges, a flat table upon which the nowel rests having trunnions at its ends, standards

20 in which the trunnions are journaled, a flat plate to fit upon the cope, mold-sections having core-prints extending to the table and the

plate and a core having ends to pass through the prints and bear against the table and the plate, the flask having a gate upon its side to 25 receive metal in its vertical position.

4. In a mold for hollow castings the combination of a nowel and a cope each having straight edges, a table to support the nowel having perforations at its ends, a plate to fit 30 upon the cope having perforations to come opposite the perforations in the table, mold-sections having core-prints extending to the table and the plate respectively to register with the perforations therein, and a core having projections extending through the prints and bearing against the table and the plate to center the core in the flask, and channels running through the core and registering with the perforations in the table and the plate.

TIMOTHY HOLLAND.
